PAINTING INSTRUMENT

Arthur L. Kline, Detroit, Mich., assignor to
 Packard Motor Car Company, Detroit, Mich.,
 a corporation of Michigan

Application April 1, 1929. Serial No. 351,493

14 Claims. (Cl. 91—62.6)

This invention relates to painting instruments and more particularly to striping instruments.

An object of the invention is to provide an instrument adaptable for applying a stripe to a bead or to a surface adjacent a bead.

Another object of the invention is to provide an instrument having means for adjusting the nozzle laterally.

Another object of the invention is to provide an instrument having an operating means provided with a plurality of engaging faces for maintaining the instrument in proper relation to the work.

Yet another object of the invention is to provide a striping instrument having an oscillatory nozzle combined with means for retaining the nozzle in position and restricting the oscillatory movement thereof.

A further object of the invention is to provide a striping instrument having a member positioned for reciprocation transversely with respect to the body of the instrument adapted to support a nozzle for oscillation, the nozzle being retained upon the member and restricted in its oscillatory movement and provided with means for supporting the discharge end thereof in spaced relation to the work and means for disengaging the nozzle from the work.

A further object of the invention is to provide a striping instrument having a reciprocatory support provided with a chamber having inlet and outlet ports and a nozzle positioned on the support having a passage communicating with the outlet port and means for retaining the nozzle upon the support and restricting the oscillatory movement thereof.

Yet a further object of the invention is to provide a nozzle for a striping instrument having means positioned in the discharge end thereof adjacent the passage adapted to support the discharge end of the nozzle in spaced relation to the work.

Yet a further object of the invention is to provide an oscillatory nozzle for a striping instrument having means for supporting the discharge end of the nozzle in spaced relation to the work, means for retaining the nozzle on the instrument and restricting the oscillatory movement thereof and means for disengaging the nozzle from the work.

Still a further object of the invention is to provide operating elements for a striping instrument comprising a disk having a plurality of circumferential faces.

And yet a further object of the invention is

to provide a striping instrument having an operating element for a striping instrument comprising a disk having an annular shoulder provided with a beveled face adaptable for engaging a plurality of surfaces simultaneously.

Other objects of the invention will appear from the following description taken in connection with the drawing, which forms a part of this specification, and in which:

Fig. 1 is a side elevation of an instrument embodying the invention;

Fig. 2 is a back elevation, partly broken away and partly in section, the section being taken on line 2—2 of Fig. 1, illustrating the instrument in operative position in coaction with a bead;

Fig. 3 is a transverse sectional view taken on line 3—3 of Fig. 2;

Fig. 4 is a side elevation, partly broken away and partly in section, the driving disk or operating element and the container being removed.

Referring to the drawing for more specific details of the invention, 10 represents a body portion comprising a rectangular block having a notch or slot 11 and a pump outlet channel 10^a 80 therein. A plate 12 is fitted in the notch and positioned in the plate is a pump mechanism 13. A cover plate 14 having a pump inlet channel 14^a is positioned in the notch 11 over the pump mechanism 13 and the plates and body portion 85 are secured together as by screws 15 or in any other suitable manner.

The pump mechanism comprises intermeshing gears, one of which is mounted on a shaft 16 which has keyed or otherwise secured thereto an operating roller 17. As shown, the roller 17 has a circumferential face 18, and an annular shoulder 19 with a beveled face 20. The circumferential face 18 is adapted to engage a flat surface and the beveled face 20 is adapted to engage the side of a bead 21 as shown in Fig. 2. The object of this structure is to provide a driving means which by virtue of a plurality of engaging faces will maintain the instrument in perfect alignment when coacting with a bead as 100 the guiding means.

Positioned transversely in the body portion in parallel relation to the shaft 16 is a double diameter bore 22 and positioned in the bore of the larger diameter is a sleeve 23, the inner diameter of which is equal to the diameter of the smaller bore. The sleeve 23 has a press fit in the bore 22 and the inner end thereof is in spaced relation to the shoulder formed at the junction of the smaller and larger bores. Communicat- 110

ing with the annular passage 23^a formed by this shoulder and said end of the sleeve 23 is a passage 22^a communicating with the outlet of the pump mechanism.

5 Positioned in the smaller transverse bore and the sleeve is a reciprocatory member 24 having a cutaway portion 25 which forms with the wall defining the bore in the sleeve, a passage 26. The reciprocatory member 24 is also provided 10 with a chamber or passage 27 having an intake port 28 communicating with the passage 26 and an outlet port 29, the object of which will hereinafter appear. As shown, the member 24 is axially bored and the bore is closed by a plug 30 15 and inlet and outlet ports are arranged in the respective ends of the member as shown in Fig.

2. The reciprocatory member 24 is provided with a radial flange 31 and fitted on the end of the reciprocatory member for oscillation is a cup 20 32, the rim of which engages the flange 31. The cup 32 has positioned thereon a nozzle 33 provided with a passage 34 communicating with the outlet port 29 by means of a passage through the wall of the cup.

25 The nozzle has a press fit on the cup and a coil spring 35 is positioned on the cup intermediate the nozzle 33 and the radial flange 31. As shown, one end of the spring 35 is secured in the shank of the nozzle and the other end of the 30 spring is secured in the face of the flange. This spring serves to retain the cup upon the reciprocatory member and to depress the nozzle in engagement with the work and suitably secured to the shank of the nozzle is a lever or handle 36 35 by means of which the nozzle may be disengaged from the work.

40 Positioned in the body portion 10 transversely with respect to the bore 22 is a bore 37 having positioned therein a plug 38 provided with a lead washer or face 39 adapted to engage the cutaway portion 25 on the reciprocating member 24. The plug 38 is secured in position by a pin 40 and may be clamped against the reciprocating member 24 by a set screw 41 to secure the member 45 against movement after it has been adjusted laterally to the desired position.

50 The cover plate 14 has formed thereupon a boss 42 provided with a bore 43 communicating with the intake of the pump mechanism 13 and threaded in the bore 43 is a container 44 having a cap or cover 45 provided with the usual vent, not shown.

55 The instrument is movable on and operated by the roller 17 with movement over the surface or along the bead to be striped. Said roller engaging or riding on the surface rotates to actuate the pump gears and forces the feed of the paint or other liquid from the container 44 into the channeled member 24 and out through 60 the nozzle. This feed is continuous through pump inlet channel 14^a, and pump outlet channel 10^a, thence through passage 22^a into the annular space or passage 23^a and finally along passage 26 through opening 28 into the member 24. Discharge from the latter through the nozzle of course occurs through the opening 29.

65 As the pump gears are actuated by the roller engaging a surface, it follows that the rate of feed will vary directly with the rate at which the instrument is moved over the surface. In this movement the roller serves also to guide the instrument along a bead for even and straight line striping as already explained.

70 Although this invention has been described in connection with certain specific embodiments,

the principles involved are susceptible of numerous other applications that will readily occur to persons skilled in the art. The invention is, therefore, to be limited only as indicated by the scope of the appended claims.

Having thus described the various features of my invention, what I claim as new and desire to secure by Letters Patent is:

80 1. A striping instrument comprising a cylindrical member, a reciprocatory member in the cylindrical member having a chamber provided with an inlet and an outlet, the reciprocatory member having a cutaway portion in which the inlet is positioned and a nozzle on the member having a passage communicating with the outlet.

85 2. A striping instrument comprising a cylindrical member having an inlet, a reciprocatory member in the cylindrical member having a cutaway portion coacting with the wall of the cylindrical member to provide a passage communicating with the inlet, a chamber in the reciprocatory member providing an inlet and an outlet, the inlet communicating with the passage and a nozzle on the member having a passage communicating with the outlet.

90 3. A striping instrument comprising a body portion, a pump positioned therein, the body portion having a transverse bore communicating with the outlet of the pump, a reciprocatory member positioned in the transverse bore, the reciprocatory member having a cutaway portion and a chamber with an inlet and an outlet, a nozzle on the reciprocatory member having a passage communicating with the outlet for the chamber.

95 4. A striping instrument embodying a container, a nozzle having feed passage connection with the container, pumping elements in the feed passage line, means actuating the pumping elements and on which the instrument is movable over a surface, and means including a 100 110 115 120 125 130 135 140 145 150 155 160 165 170 175 180 185 190 195 200 205 210 215 220 225 230 235 240 245 250 255 260 265 270 - for independent oscillatory movement and by which it is projected in spaced relation to the instrument's path of movement, means retaining the nozzle on said member and normally holding its discharge end in engagement with the work, and means for raising said end of the nozzle from engagement with the work. 5
8. A striping instrument comprising a supporting body, a fluid container thereon, a longitudinally chambered member slidably adjustable laterally of said body and forming part of a feed conduit therethrough from the container, means including a roller and pumping elements for feeding through the conduit by pressure variable directly with the rate at which the instrument is moved over a surface, and a discharge nozzle mounted on said chambered member for adjustment in spaced relation to the instrument's path of movement; said roller being adapted to engage surfaces in different planes and serving to guide the instrument along the different surfaces. 10
9. In an instrument for applying a stripe upon a surface traversed thereby, a body, a nozzle, and a slidable mounting for the nozzle associated with and extending laterally from the body, the adjustment of said mounting regulating the distance between the nozzle and the body. 15
10. In an instrument for applying a stripe, a body, a pump in the body, a fluid container fixed to the body in communication with the pump, a support extending laterally from one side of the body, said support telescoping in the body and being axially adjustable laterally, a nozzle carried by the support, said support and body having a passageway therein leading from the pump to the nozzle, a supporting roller carried by the body, and driving mechanism between the roller and the pump. 20
11. In an instrument for applying a stripe upon a surface, a body, a roller carried by and supporting the body upon the work to be striped, a nozzle extending in a plane adjacent the roller for exuding fluid directly upon a surface traversed, an axially adjustable shaft extending from the body on which the nozzle is pivotally mounted, and means for feeding paint through the nozzle. 25
12. In a molding striping instrument, a body having a nozzle support extending from one side thereof, a fluid dispensing nozzle mounted on the support in spaced relation with the body and a roller carried by the body, said roller having a face adapted to roll on a work surface adjacent the molding, and a bevelled face adapted to roll against the side of the molding, a portion of the roller between the faces being relieved to clear the base portion of the molding. 30
13. In a striping instrument, a body, a shaft extending from the body, a cap loosely mounted on the shaft and a nozzle fixed to the cap, and spring means retaining the cap axially on the shaft, and acting in a direction to press the nozzle toward the work surface when the instrument is in striping relation therewith. 35
14. In a striping instrument, a body, a shaft extending laterally from the body, said shaft and body having communicating passages therein through which paint is moved, a nozzle pivotally mounted on the shaft in spaced relation with the body and in communication with the passage therein, and a spring coiled around said shaft and fixed at one end thereto, the other end of the spring being associated with the nozzle in a relation to press the outlet end of the nozzle against the surface to be striped when the instrument is in operative relation therewith. 40
